UNITED STATES PATENT OFFICE.

CHARLES E. SUTTON, OF TOLEDO, OHIO.

POWER MECHANISM FOR PUMPING OIL-WELLS.

SPECIFICATION forming part of Letters Patent No. 627,604, dated June 27, 1899.

Application filed March 8, 1897. Serial No. 626,405. (No model.)

To all whom it may concern:

Be it known that I, CHARLES E. SUTTON, of Toledo, county of Lucas, and State of Ohio, have invented certain new and useful Improvements in Power Mechanism for Pumping Oil-Well; and I do hereby declare that the following is a full, clear, and exact description of the invention, which will enable others skilled in the art to which it appertains to make and use the same, reference being had to the accompanying drawings, and to the numerals of reference marked thereon, which form part of this specification.

This invention relates to a power mechanism for pumping oil-wells of that class where-in a number of wells are operated or pumped from a single power mechanism; and the objects of the invention are to simplify the several parts of the power mechanism and to arrange the same to provide for an even and maximum application of power transmitted to the pumping mechanism.

The invention therefore consists in the parts and combination of parts shown in the drawings, described in the specification, and more particularly pointed out in the claim.

In the drawings, Figure 1 is a top plan view of my invention. Fig. 2 is an elevation. Fig. 3 is a plan view, partly in section, showing the semirevolute pitman-wheel with the quadrant-rack attached thereto and the rack-bars of the pitmen in engagement therewith. Fig. 4 is a side elevation of one of the pitman-arms, showing in dotted lines the conditions inverted. Fig. 5 is a central vertical section through the semirevolute wheel, showing its axial foundation and the antifriction-bearing supports, together with the quadrant-rack bars and pitman-rack-bar guides. Fig. 6 shows a modified construction in which the pitmen are shortened in their connection with the rack-bar and driven by a link-motion.

I provide the bed-frame 1 of the engine and a section 2, in which are journaled the shafts of the gearing, with a section 3, attachable thereto, in which is journaled the semirevolute pitman-wheel.

Power is transmitted from the engine 4 in any preferred manner to a pinion meshing with a gear 6, loosely mounted upon a shaft 7 and adapted to be engaged to revolve therewith by means of a clutch 8, controlled by a

lever 9 and normally held in engagement with the friction-surface 10 of gear 6. Upon shaft 7 is secured a pinion 11, engaging with a gear 12, mounted upon a shaft 13, having crank-arms 14 upon each end of the said shaft. To crank-arms 14 are pivoted pitmen 15, connected at their outer ends with rack-bars 16.

Rack-bars 16 mesh with toothed segments 18, secured in diametric relation upon a pitman-wheel 19, to which are attached a plurality of pitman-arms 20, by which pitmen 21 may be connected by means of straps 22, engaging upon either an outer pivot 23 for a long stroke or inner pitmen 24 for a shorter stroke.

So far as described it will be observed that power being transmitted to pinion 5 by means of the engine gear 6 is revolved, and consequently pinion 11 and gear 12, thereby revolving shaft 13 and communicating a reciprocating motion to the pitmen 15 and rack-bars 16, with the effect of imparting a semirevolution to wheel 19 and consequently a reciprocating motion to pitmen 21, connected with the pumps. Arms 20, as shown in Fig. 4, are formed with a portion 26 joining the parallel horizontal portions 25 and 27, whereby the arms are reversible—that is to say, the portion 26 may incline upward, as shown in full lines, or may be reversed, as shown in dotted lines. The rack-bar is housed and caused to engage with the toothed segments by means of a casting 28, formed integral with a base-plate 29 and an inwardly-projecting horizontal plate 30, upon which the rack-bar rests, there being a plate 31 secured to the casting 28 at its top. Wheel 19 is supported, preferably, upon four antifriction-rollers 32, formed with inclined peripheries to correspond with an inclined face of the under side bearing portion of the wheel 19. Wheel 19 is preferably formed upon a conical bearing 33, upon which a conical shell 34 rests, and is held in position by means of a threaded rod 35, extending axially through the same.

In some instances it may be desirable to give accelerated speed to the engine prior to coupling with the pitman-wheel 19, as in the event of heavy producing wells. In this instance the clutch 8, which is normally in engagement with gear-wheel 6, thereby causing it to move in unison with shaft 7, is with-

drawn from the friction-surface 10 of wheel 6, thereby allowing great momentum to be obtained before throwing it again into engagement.

- 5 In some instances it is desirable to couple the power in close relation with the pitman-wheel 19. I have therefore provided a link-movement directly attachable to cranks 14, comprising the link 36, in which the crank-
10 arm travels, thereby imparting a reciprocatory movement to the rack-bar 16 direct.

I have found in practice that a square follower 37 in the link 36 presents a greater bearing-surface and is conducive to longer wear
15 of the bearing, and therefore obviates a tendency to lost motion heretofore formed in a round bearing.

What I claim is—

Means for pumping oil-wells comprising a
20 base having an annular upwardly-projecting bearing near one end and in its transverse

center, antifriction-rollers journaled in bearings secured to the base, a pitman-wheel journaled upon the upwardly-projecting bearing and resting upon the antifriction-rollers at a 25 point near its periphery, housings carried by the base upon each side thereof, rack-bars arranged in the housings, means for reciprocating the rack-bars, toothed segments carried by the pitman-wheel with which the rack-bars mesh, arms secured to and projecting radially from the pitman-wheel, and pitmen connecting the outer end of said arms and the pumping mechanism of oil-wells.

In testimony that I claim the foregoing as 35 my own I hereby affix my signature in presence of two witnesses.

CHARLES E. SUTTON.
